J. Henderson
ATTORNEY

UNITED STATES PATENT OFFICE.

AUGUSTINE DAVIS, OF JAMAICA, NEW YORK, ASSIGNOR TO AMERICAN LOCKER COMPANY, OF BOSTON, MASSACHUSETTS, A CORPORATION OF DELAWARE.

LOCK.

Application filed May 12, 1922. Serial No. 560,287.

To all whom it may concern:

Be it known that I, AUGUSTINE DAVIS, a citizen of the United States, and a resident of Jamaica, Long Island, in the county of 5 Queens and city and State of New York, have invented a certain new and useful Improvement in Locks, of which the following is a specification.

The invention relates to locks, and particularly to locks such as are used in coin-controlled lockers. In these lockers the locker compartments are built in tiers with the coin locks for the compartment doors of each vertical row set in openings in the 15 appurtenant stile member. The plates of the locks are mounted in the stile so that they can be readily taken out of the openings for replacement in event of loss of a key, and it has been customary to provide 20 locking means for securing them in the openings, such locking means involving a vertically extending locking rod common to the vertical series of locks and a key-lock at one point in the frame for locking this 25 rod or controlling access thereto. Considerable trouble has arisen from the use of such locking rods, and this difficulty the present invention aims to overcome, which is accomplished by providing a directly-carried locking-in lock for each of the door 30 locks.

In the accompanying drawings, forming a part hereof:

Fig. 1 is a front elevation of a lock embodying the invention; and

Fig. 2 is a side elevation thereof, with portions broken away and in section, set in the opening of the frame or stile member, which is shown in vertical section.

The drawing illustrates a form of coin-controlled locker-lock in commercial use, the same comprising a vertically elongated plate 2 carrying a key-lock 3 having a bolt 4 which when projected locks the locker door 45 (not shown). The lock is controlled by a coin deposited in the coin-entrance 5, and in the particular form illustrated the bolt

is shot as the result of turning the knob 6 after deposit of the coin, the key being then removable, and is subsequently retractible 50 by operation of the key-check 7. The particular manner in which the operation of the lock and the removal of the key are controlled by the coin is, however, not essential; and other forms of coin-controlled 55 locker locks may be employed.

The plate 2 is set in an opening in the face of a stile member 8, beneath one edge of which, as the lower edge, it is caught by suitable fixed lugs 9. At another point it 60 is locked in the opening by retractible locking means, which is here constituted by a key-lock 10 which is carried by the plate 2. The bolt 11 of this lock when retracted permits the lock structure as a whole to be 65 tilted out of the opening, and when projected catches behind the edge of the opening or in a suitable keeper 12, so that the locker lock is securely fastened against displacement. The attendant or an authorized 70 person is provided with a special key which enables him to unlock and lock the locking-in lock 10 of the several locker locks, in order to replace them when necessary, or to afford access to the locker for a patron 75 who may have lost his key. It will be seen that each locker lock is positively locked in place by this system, and that any lock can be unlocked for removal without in any way affecting other locks in the vertical row, 80 which is an advantage over existing practice.

The locking-in lock is shown at the top of the removable lock panel, but may be disposed in other positions thereon.

What I claim as new is:

A lock comprising a plate adapted to be placed in an opening and carrying a lock mechanism having a bolt for locking a closure, in combination with a second key 90 lock carried by the plate and having a bolt for locking the plate in its opening.

AUGUSTINE DAVIS.
